PETER L. WEIMER, OF LEBANON, PENNSYLVANIA.

Design No. 4,834, dated April 18, 1871.

DESIGN FOR A STEAM-ENGINE.

The Schedule referred to in these Letters Patent and making part of the same.

To all whom it may concern:

Be it known that I, PETER L. WEIMER, of Lebanon, in the county of Lebanon and State of Pennsylvania, have invented a new and original Design of a Steam-Engine; and I do hereby declare that the following is a full, clear, and exact description of the same, which will enable others skilled in the art to make and use the same, reference being had to the accompanying drawing forming part of this specification.

The photograph represents a perspective view of my new design of a steam-engine.

The nature of my design is fully represented in the accompanying photographic illustration, to which reference is made.

I claim as my invention—

The design of a steam-engine, as shown.
